(57) **CLAIM**

I claim the ornamental design for a compression patella sleeve, as shown and described.

DESCRIPTION

FIG. 1 is a perspective view of a compression patella sleeve, as worn on the leg of a user;

FIG. 2 is a front view of the compression patella sleeve;

FIG. 3 is a rear view of the compression patella sleeve; and,

FIG. 5 is a right side view of the compression patella sleeve. The broken line showing of a human leg in FIG. 1 is for the purpose of showing environment which forms no part of the claim. The broken line showing on the compression patella sleeve is for the purpose of illustrating portions of the sleeve which form no part of the claim. The patterns on the sleeve represent claimed yarn and thread contrast.
